WINDOW VENTILATING LOCK

Samuel H. Melnick, Chicago, Ill.

Application April 26, 1949, Serial No. 89,645

3 Claims. (Cl. 292—202)

1

My invention relates to improvements in window ventilating locks of the type whereby the lower and/or upper window sashes may be opened short distances for purposes of ventilation, yet are locked against further opening. Such locking devices are often referred to and sold under the name of "window burglar locks."

A principal object of my invention is to provide a window ventilating lock of strong, durable construction which employs no springs or spring arrangements to lock the locking member in place.

Another object of my invention is to provide a window ventilating lock which cannot be moved to the unlocked position from the outside of the window.

Another object is to provide a window ventilating lock which cannot be deflected to the unlocked position even when the window is raised suddenly and with such great force that parts of the lock are bent.

Another object is to provide a window ventilating lock which is inexpensive to manufacture, easy to install, neat in appearance, and convenient to use.

When installed on a window of conventional design, my invention includes an arm which extends from one of the vertical ledges of the upper window sash, a bracket member projecting from the free end portion of the arm and lying adjacent to the window glass, and a rod or stop member pivoted to the bracket member so as to be capable of extending over the upper ledge of the lower sash. The rod is further adapted to turn on its longitudinal axis to various positions, and when in one position can be inserted within an edge opening in the edge of the arm. When the rod is then turned on its longitudinal axis to a second position, it is locked securely to the arm and cannot be moved to the unlocked position until such time as the rod is rotated back to the original position or an alternate position corresponding thereto.

In order that my invention may be more fully disclosed, reference is had to the accompanying drawing which illustrates one form of apparatus embodying the foregoing and such other principles, advantages or capabilities as may be pointed out as this description proceeds, or as are inherent in the present invention. For purposes of clarity in exposition, the following description is explicit, and the accompanying drawing is detailed, but it is distinctly to be understood that said exposition is illustrative only, and that my invention is not restricted to the particular

2

details recited in the specification or shown in the drawing.

In the drawing:

Figure 1 is a fragmentary perspective view showing one embodiment of my invention as it appears when installed on a window of conventional design and when placed in the locked position;

Figure 2 is a front elevational view of the embodiment of Figure 1, with the stop member in the unlocked position;

Figure 3 is a front elevational view with the stop member in the locked position;

Figure 4 is a plan elevational view as per Figure 2;

Figure 5 is a plan elevational view as per Figure 3; and

Figure 6 is a side elevational view as per Figures 3 and 5.

Like reference numerals designate like parts in the drawing and in the description thereof following hereafter.

Referring now to the drawing, the embodiment shown includes a plate 10 having a plurality of counter sunk openings 11 therein whereby the plate 10 may be readily fastened by screws 11a to a vertical ledge 12 of the upper sash of a window (Figure 1). When the plate 10 is fastened to the ledge 12 in this manner, the arm 13 projects free of the ledge 12. Secured to the arm 13 and adapted to lie adjacent the window glass 14 is a substantially U-shaped bracket member 15 (Figures 4 and 5). The leg 16 of the bracket member 15, and the arm 13 contain an edge opening 17 comprised of a substantially circular portion 18, and a throat 19 the width of which is less than the internal diameter of the circular portion 18.

Projecting from the leg 20 of the bracket member 15, are two ears 21 and 22. Each of the ears 21 and 22 is substantially perpendicular to the arm 13 and extends toward said arm. Each of the ears 21 and 22 is further characterized by a central opening 23 which pivots one of the pivot lugs 24 that extend from opposite ends of the link 25.

A rod 26 is rotatably secured to the link 25, and forms a stop member which is adapted to overlie the upper ledge 27 of the lower sash of the window. As is best shown in Figures 2 and 4, the rod 26 is provided with a pair of substantially parallel flats 28, 28 intermediate the end fixed to the link 25 and the knurled end 29.

The pivot connection between the link 25 and the ears 21 and 22 permits turning the rod 26 from the position of Figure 4 to that shown in Figure 5.

When the rod 26 is rotated on its longitudinal axis to the position of Figures 2 and 4, the effective thickness of the rod 26 is reduced by the flats 28, 28 sufficiently to permit the rod 26 to traverse the throat portion 19 of the edge opening 17 and enter the circular portion 18. By then turning the rod 26 on its longitudinal axis, into the position shown in Figure 5, the effective thickness of the rod 26 is increased to the normal diameter of said rod. When my window ventilating lock is placed in this latter position, it is apparent that the rod 26 is securely locked to the arm 13 and cannot move through the throat portion 19.

When the rod 26 is in the locked position, it overlies the upper ledge 27 and permits the lower sash of the window to be raised only a short distance. Or, conversely, the upper sash of the window can be lowered until the rod 26 contacts the upper ledge 27. When the window is thus opened, the rod 26 cannot be moved from the locked position by inserting a blade between the upper and lower sashes and pushing the rod 26 to one side. Furthermore, should the window be raised suddenly, or for any other reason considerable upward or downward force be exerted on the rod 26, my novel locking arrangement prevents deflection of the rod 26 to the unlocked position.

In addition, my invention is characterized by unusual strength and durability. These characteristics are due in large measure to the fact that the plate 10, which can be made very strong and rigid against bending, braces the rod 26 and takes the brunt of the load imposed on said rod 26. Thus the pivot means assume only a small portion of the load, rather than the entire load as in the case of the conventional prior art window ventilating locks. If unusually large loads are imposed upon the rod 26, the lock still will not fail, even though the ears 21 and 22 are bent. In the case of the prior art devices, any bending of the pivotal supports of the locking member almost invariably results in the locking member being broken from the rest of the window lock.

Advantageously, my construction lends itself well to low cost mass production, since all of the parts may be stamped or made on screw machines or other automatic machine tools.

Having thus fully disclosed my novel window ventilating lock, and demonstrated its utility by reference to a specific embodiment thereof, I claim:

1. A window ventilating lock, comprising: a bracket adapted to be fastened to a window frame and including a plate portion adapted to project free of said window frame, a substantially U-shaped arm one leg of which abuts said plate portion, said leg and said plate portion in abutment therewith having a common edge opening comprising a substantially circular portion and a throat portion extending to said edge, the width of said throat portion being less than the internal diameter of said circular portion, a pair of ears extending, respectively, from opposite edges of the other leg of said U-shaped arm and toward said plate portion, a link pivotably secured to and disposed between said ears, and a rod projecting from said link and pivotably secured at one end thereof to said link, the diameter of said rod being only slightly less than the internal diameter of said circular portion, said rod having two substantially parallel flats thereon so propor-

tioned and arranged that said rod may be swung through said throat portion into said circular portion, whereby rotating said rod relative to said link locks said rod to said plate portion, said rod being of a length such that the free end thereof projects beyond said plate portion.

2. A window ventilating lock, comprising: a bracket adapted to be fastened to a window frame and including a plate portion adapted to project free of said window frame, said plate portion having an edge opening comprising a substantially circular portion and a throat portion extending from said edge to said circular portion, the width of said throat portion being less than the internal diameter of said circular portion, a link and means hingedly securing said link to said bracket for rotation about an axis spaced from and substantially parallel to said plate portion, a rod rotatably secured at one end thereof to said link, the longitudinal axis of rotation of said rod being substantially perpendicular to the axis of rotation of said link, the diameter of said rod being only slightly less than the internal diameter of said circular portion, said rod having intermediate the two ends thereof two substantially parallel flats whereby said rod may be turned to traverse said throat portion, and whereby said rod may be locked to said plate portion upon turning said rod so that said flats are misaligned with the sides of said throat portion.

3. A window ventilating lock, comprising: a bracket adapted to be fastened to a window frame and including a plate portion adapted to project free of said window frame, said plate portion having an edge opening comprising a substantially circular portion and a throat portion extending from said edge to said circular portion, the width of said throat portion being less than the internal diameter of said circular portion, a link and means hingedly securing said link to said bracket for rotation about an axis spaced from and substantially parallel to said plate portion, a rod rotatably secured at one end thereof to said link, the longitudinal axis of rotation of said rod being substantially perpendicular to the axis of rotation of said link, a portion of said rod intermediate the two ends thereof having a first dimension in one plane which is only slightly less than the diameter of said circular portion, and a second dimension at substantially right angles to said first dimension which is less than the width of said throat, whereby said rod may be inserted in said edge opening upon turning said rod so that the smaller dimension of said rod portion is aligned with said throat, and whereby said rod may be locked to said plate portion upon turning said rod approximately 90 degrees.
